UNITED STATES PATENT OFFICE.

CHARLES W. BARNABY, OF NEW YORK, N. Y.

TYPE-WRITING MACHINE.

1,198,097.

Specification of Letters Patent. Patented Sept. 12, 1916.

Application filed December 23, 1911. Serial No. 667,537.

To all whom it may concern:

Be it known that I, CHARLES W. BARNABY, a citizen of the United States, residing in the first ward, borough of Richmond, county of Richmond, city of New York, and State of New York, have invented a new and useful Type-Writing Machine, of which the following is a specification.

My invention relates to improvements in the manner of mounting the paper roll, or platen, for typewriting and similar recording machines in which letters, and other characters and marks, are recorded upon a sheet or roll of paper or other material: and the objects of my improvement are, first, to reduce the size and weight of portable machines, of which the folding typewriter, Patent No. 754,272, Rose, March 8, 1904, is an example; second, to provide for the insertion of a wider sheet than will be admitted by such machines as heretofore constructed; third, to permit the ready substitution of other platens, mailing tubes, or other objects with cylindrical surface, in the place of the regular platen so that they may be written upon. I attain these objects by the mechanism illustrated in the accompanying drawings in which—

Figure 1 is an end view and Fig. 2 a front view illustrating the application of my invention to the folding typewriter referred to above; Figs. 3, 4, 5 are end, front and end views respectively, of a modified application of my invention; and Fig. 6 is a back view and Fig. 7 an end view of my preferred adaptation of my invention to compact, portable machines.

As my invention relates only to the platen and the carriage by which it is carried and controlled, I have not considered it essential to show a machine complete in all of its details and therefore merely show a few principal members of the machine proper, such as will enable those versed in the art to readily understand the application and operation of my invention.

Similar letters refer to similar parts throughout the several views.

The platen R is supported and controlled in whole or part by the rolls N, N', O, O' and springs Q, Q' which form a part of the carriage. Other parts of the carriage are the tie and slide piece J, the tie L, the end frames P, P', the carriage wheel K and rack M, the ties J, L forming the principal longitudinal members of the carriage frame.

Referring to Figs. 1, 2:—A, A', A'' are parts of the main frame; B, C, D, E, F are representatives, respectively, of the banks of keys, key-levers, links, type-bars and types; 60 W, W' are the guide posts and V, V' the guide stems whereby the carriage frame G is connected with the main frame in such manner as to admit of its vertical adjustment, by means of the key and lever Y, X, to 65 correct positions for the several characters on the type F when the latter is thrown, by pressing the key B, into writing position F'. H, H' are hinge arms attached to the carriage supporting frame G and guide stems 70 V, whereby the carriage frame may be swung on the pivot Z to the position H' R', to put the machine in compact form for convenient transportation. The parts G', G'' of the carriage frame G serve as tracks 75 upon which the carriage wheel K and slide rod J travel. Guards I, I' prevent the carriage from lifting off of the tracks.

As is understood by those familiar with typewriters as heretofore manufactured, the 80 platen revolves on a pivot in bearings at each of its ends similar to *a* and *a'*, Figs. 4, 5, a knob-like handle T being provided at one or both ends whereby the platen may be rotated by hand, also a ratchet wheel S 85 whereby the platen is rotated by suitable adjustable mechanism which gives it a predetermined part of a revolution to the extent of one, two or more ratchet teeth, according to the spacing desired between the lines 90 written. It is obvious that in my invention as exemplified in Figs. 1, 2 these platen end pivots and bearings are dispensed with and the platen centered and rotated by a system of rolls N, N', O, O' arranged about its periphery, the rolls O, O' being mounted in springs Q to give the required pressure between the system of rolls and platen. 95

It has heretofore been common practice to surround the platen with similar rolls for 100 the purpose of holding the writing paper in contact with the platen so that when the platen is rotated it will, due to the surface friction of the paper pressed against it by the rolls, impart its peripheral movement to 105 the paper, which, in turn, imparts its motion to the rolls, causing them to rotate at the same peripheral speed as the platen. In my invention I reverse the order of this action by first imparting motion to one or 110 more of the small rolls, which, in turn, impart the motion to the paper and platen. T,

Fig. 2, shows a handle attached to the end of the shaft of roll N, Fig. 1, by means of which the roll may be rotated to the effect that motion is imparted to the whole roll system including the platen and sheets of paper placed between the platen and small rolls.

In Figs. 3, 4, 5 is shown another manner of applying my invention in which the platen is pivotless at one end only the other end being mounted on a pivot, α , Figs. 4, 5, in the usual manner. In this case the motion can either be imparted to the platen first through the handle T or ratchet S, or to one or more of the small rolls, as best suits the requirements of the particular machine to which the invention is applied.

Figs. 6, 7 show my preferred manner of applying my invention to portable machines. The pivotless platen is mounted in an open ended carriage, centered and controlled by the rolls N, N', O, O'; motion is imparted to the roll system through the auxiliary shaft c b' either by means of handle T, Fig. 6, or the ratchet wheel S. The handle T is mounted on the rod b which is telescoped into the hollow part c of the auxiliary shaft and engages, rotatively, therewith by the pin e in the rod b which slides in the slot d in the hollow shaft c. This slotted connection permits the rod b to slide endwise in hollow shaft c, thus permitting the adjustment of the handle T to a greater or less distance from the end of the carriage and platen for the purpose explained hereafter.

The ratchet wheel S is attached rigidly to the shaft b' which in turn is rigidly attached to the hollow part, c, of the shaft so that all rotate together as one unit. To this shaft is also rigidly connected the gear wheel g which meshes with and drives pinion f attached rigidly to the shaft of the roll N. The gear wheel g is also connected with the pinion j on the shaft of the roll N' through the two intermediate pinions h, i. It is obvious that when, with this train of gear, motion is given to shaft c b', the two rolls N, N' will be positively driven in unison, both in the same direction of rotation, thus driving the platen and feeding the paper more positively than when only one roll is positively operated, as in Fig. 2.

The platen is caused to rotate as desired by means of the handle T, Fig. 6, or by means of the line spacing mechanism as follows:—The upper end of lever l, at the front or writing side of the platen, is forced downward by the operator's finger, which causes the link r to swing on the pivot and toward shaft b' and the arm z of the bell crank n, to which the lever l is connected, to swing on the shaft b' and toward and against the stop pin u which is attached in a fixed position to the end frame P. At the

same time the pawl m at the end of the other arm of bell crank n moves forward, and, being thrown by the spring o into engagement with a tooth of the ratchet wheel S, gives the latter a rotative motion the extent of which is determined by the distance which the bell crank n swings before its arm z strikes the stop pin u. When the finger is removed from lever l it is returned to the normal position shown in the drawing, Fig. 7, through the action of the spring p. The tail end of pawl m at the same time comes in contact with the pin v throwing the pawl out of engagement with the ratchet wheel S, leaving the roll system free to be operated by means of the handle T, Fig. 6, or otherwise, without interference on the part of the pawl m. The pins v, t are attached to the two arms of bell crank k which rotates about the center of shaft b' and is capable of adjustment to certain fixed positions through its crimped spring y in contact with the fixed pin on the end frame P of the carriage.

As has already been explained, the forward movement of the pawl m is always to one fixed point determined by the arm z of bell crank n striking the fixed stop pin u. It is now evident that, having provided means for holding the lever k in certain several positions by means of the crimped spring y, the mechanism may be adjusted to turn the ratchet wheel S to the amount of one or more teeth at a time, as desired, by merely adjusting bell crank k to the position that will so locate its pin t as to stop the arm z of bell crank n as to allow the pawl m to only recede from its advance feeding position to a point covering the number of teeth it is desired to feed at each operation of the feeding mechanism. The pivotal centers of the bell cranks k and n being coincident, it is obvious that to whatever position bell crank k is adjusted its two pins t, v are in such relation to bell crank n that whenever the arm z is in contact with pin t the tail of pawl m is in engagement with pin v and thus holding the pawl out of engagement with the teeth of ratchet wheel S.

When, in the portable typewriter of the form illustrated in Fig. 1, the platen R and carriage frame support G are folded to the position indicated at II'', R', it is obvious that the space occupied by the machine is considerably reduced. It so happens that the length of platen together with its end bearings and handles on the extended ends of its pivots, as heretofore constructed, when given the free space between its end bearing frames which is commercially required for the reception of sheets of the desired width, is several inches longer than the width of main frame of the machine required to house what is known to the trade as the standard keyboard and other mechanism.

It also so happens that by omitting the end pivots, bearings and handles, and still retaining a length of platen sufficient to give a written line of some 70 to 74 spaces, as 5 commercially required in standard machines, I am enabled by the application of my invention to keep the extreme length of the platen and its housing down to the minimum of the main frame which will house 10 the standard keyboard. The application of my invention therefore materially reduces the width of typewriting machines without reduction of their capacity.

A further advantage of my invention is 15 that the elimination of end bearings and the mounting of the platen in an open ended carriage, as exemplified in Figs. 1, 2, 6, 7, sheets of practically unlimited width may be inserted in the machine, as it is obvious 20 that the sheet passed around the platen may extend any distance beyond either end of the platen without interference on the part of any element of the machine. As the extension of the paper on the end of the platen 25 adjacent to the handle T, Figs. 2, 6, is placed makes it less convenient to manipulate said handle, I prefer, in the application of my invention, to provide for the extension of handle T which is accomplished in Fig. 6 30 by telescoping the rod *b*, to which the handle is attached, into the shaft *c*, as has already been explained, this provides means for placing handle T beyond the limit of a sheet which projects materially beyond the adjacent 35 end of the platen. At the end of the platen farthest removed from the handle T, Figs. 2, 6, there is absolutely no part of the machine to interfere with unlimited extension in the width of the sheet.

40 Another advantage of the axially adjustable handle T is that when said handle is pushed inwardly, the space *b* (see Fig. 6) permits it to be brought within the lateral limit of the platen R, thus rendering it 45 more compact for packing purposes.

Figs. 3, 4, 5 exemplify the application of my invention to machines where reduction in space occupied by the machine is not a paramount object. This construction admits of retaining the ordinary means of rotating the platen through the handle T and ratchet wheel S, Figs. 4, 5, placed upon a center coincident with that of the platen. The other end of the platen being pivotless 55 and mounted in an open end carriage so that sheets, long envelopes and other articles written upon may extend any required amount on the one end.

A still further advantage of my invention 60 as exemplified in Figs. 1, 7 is that the platen may be readily removed from its housing in the direction indicated by arrow *w* and may be as readily replaced, the elasticity of the springs Q, Q' allowing the rolls O, O' to recede sufficiently to permit the platen to pass

between rolls O, O' and N. As examples of the advantage afforded by the convenience with which the platen may be removed and inserted may be mentioned the opportunity it affords for replacing a platen at any time 70 by one of softer or harder material, according to the requirements of various kinds of work. It also admits of the substitution of mailing tubes, or other articles with a cylindrical surface in place of the platen and 75 writing directly on them, the open ends of the carriage permitting the insertion of an article of practically unlimited length. For such purposes it is obvious that the open ended carriage without the platen is a complete device.

In the application of my invention I do not limit myself to the exact construction herein shown and described, as many modifications in details will be apparent to the 80 artisan versed in the art, and various modifications may be made without departing from the spirit of my invention.

Having thus described my invention, I claim as new and desire to secure by Letters 90 Patent—

1. The combination with a platen, of a plurality of links pivotally mounted, one of said links being provided with suitable operating connections with said platen to transmit the line-spacing movements to said platen, and a line-spacing lever pivotally connected to each of said links, one of said links constituting a movable fulcrum for 95 said line-spacing lever.

2. The combination with a platen, of a plurality of links pivotally mounted, one of said links being provided with suitable operating connections with said platen to transmit the line-spacing movements to said platen, and a line-spacing lever pivotally connected to each of said links, one of said links constituting a movable fulcrum for 100 said line-spacing lever, the pivotal axes of said links being distant from the rotary axis 105 of said platen.

3. The combination with a platen, of a ratchet wheel, operatively connected up with said platen, a pawl for said ratchet wheel, a member carrying said pawl, a line spacing 115 lever connected to said pawl carrying member, and a link connected at one end to a fixed pivot and having its other end pivotally supporting said line spacing lever.

4. The combination with a platen, of a ratchet wheel operatively connected up with said platen, a pawl for said ratchet wheel, a member carrying said pawl, a line spacing lever connected to said pawl carrying member, and a link connected at one end to a 120 fixed pivot and having its other end pivotally supporting said line spacing lever, said line spacing lever being curved and disposed concentrically with said platen.

5. The combination with a platen, of a 125

paper feed roll rotatably supporting said platen, a ratchet wheel geared to said feed roll, a pawl for driving said ratchet wheel, a lever for mounting said pawl, a line spacing lever pivoted at one end to the pawl mounting lever, and a fulcrum link having one end pivoted on a fixed axis and its other end pivotally connected to the line space lever.

6. The combination with a platen, of a paper feed roll rotatably supporting said platen, a ratchet wheel geared to said feed roll, a pawl for driving said ratchet wheel, a lever for mounting said pawl, a line spacing lever pivoted at one end to the pawl mounting lever, and a fulcrum link having one end pivoted on a fixed axis and its other end pivotally connected to the line space lever, said line spacing lever being concentrically curved about the platen and adapted 20 by said fulcrum link to be shifted endwise about said platen.

7. The combination of a platen, a ratchet wheel operably connected with said platen, a pawl, a pawl-carrying lever, a fixed stop 25 for the advance movement of the pawl, an adjustable member carrying a pawl releasing stop and a stop for limiting the return movement of the pawl carrying lever, and means for moving the pawl carrying lever.

8. The combination with a platen, of members pivotally mounted on axes parallel to the axis of said platen, a line spacing lever connected to each of said members, a ratchet operably connected to said platen, 35 and a pawl carried by one of said members for driving said ratchet.

9. The combination with a platen, of members pivotally mounted on axes parallel to the axis of said platen, a line spacing 40 lever connected to each of said members, a ratchet operably connected to said platen, a pawl carried by one of said members for driving said ratchet, and a stop, said pawl being provided with a portion suitably arranged 45 to be engaged by said stop to remove said pawl from the ratchet in a predetermined position of said member.

10. The combination of a ratchet wheel with a pawl, pawl carrying means, a stop 50 for the advance movement of said pawl, adjustable means for releasing said pawl, an operating lever, and a guiding link for said operating lever.

11. The combination with a carriage, of an open end platen rotatably mounted thereon, and means, for rotating said platen, said means including an extensible handle.

12. The combination with a carriage, of an open end platen rotatably mounted there-

on, a shaft geared thereto to transmit rotat- 60 ing movements to said platen, and a handle extensibly connected to said shaft.

13. The combination with an open end platen, of a shaft section geared thereto, a second shaft section telescopically connected 65 to the first shaft section, and a platen rotating handle carried by the second shaft section.

14. The combination with a platen, of a ratchet connected thereto, a lever movably 70 mounted, a pawl carried by said lever for driving said ratchet, a line-spacing lever connected to the pawl-carrying lever, and a movable fulcrum for said line-spacing lever, said fulcrum moving simultaneously with 75 said line-spacing lever during the line-spacing movement.

15. The combination with a platen, of a ratchet connected thereto, a pawl for actuating said ratchet, a lever for carrying said 80 pawl, a line-spacing lever connected to said pawl-carrying lever, and a movable mount for said line-spacing lever, said line-spacing lever and said mount therefor being movable simultaneously and producing the line-spacing operation.

16. The combination with a platen, of a line-spacing handle, and means for connecting said handle to said platen, said connecting means being adapted to permit an endwise movement to said handle relative to the platen and to hold said handle against rotation relative to the platen during such endwise movement.

17. The combination with a platen, of a line-spacing handle, and means for connecting said handle to said platen, said connecting means being adapted to permit an endwise movement to said handle relative to the platen and to hold said handle against 100 rotation relative to the platen during such endwise movement, said connecting means including a member geared to said platen and a slip joint connection between said member and said handle.

18. The combination with a platen, of a line-spacing handle adjustable endwise relative to the platen, means for supporting the platen, and means for connecting said handle to the platen and permitting an endwise movement relatively thereto, while preventing a relative rotation with respect to the platen.

CHARLES W. BARNABY.
